UNITED STATES PATENT OFFICE.

PHILIP MUELLER, OF DECATUR, ILLINOIS.

SANITARY DRINKING-FOUNTAIN.

1,311,833.

Specification of Letters Patent. Patented July 29, 1919.

Application filed August 22, 1916. Serial No. 116,342.

To all whom it may concern:

Be it known that I, PHILIP MUELLER, a citizen of the United States, residing at Decatur, in the county of Macon and State 5 of Illinois, have invented new and useful Improvements in Sanitary Drinking-Fountains, of which the following is a specification.

The present invention relates to sanitary 10 drinking fountains of that type in which a bubbler head is provided from which, when the valve is operated, a drinking stream or jet is projected to a point above the bubbler head convenient for drinking, 15 and the user will not be likely to bring his mouth in contact with the bubbler head.

In order, however, to further guard 20 against possible touching of the lips to the bubbler head and increase the sanitary features of these devices, I have provided a guard so placed with respect to the orifice from which the drinking stream issues that the user cannot in the ordinary position of 25 drinking place the mouth in contact with the head, and furthermore, this fountain is so designed that the user is protected from splashing or drip, and the entire structure is so designed that all objectionable crevices are eliminated, the lodgment of contaminating 30 matter guarded against, and, finally a thorough and effective wash of all of the parts is secured by the construction which I have devised.

In the drawings herewith I have shown 35 one embodiment of my invention, and in said drawings,—

Figure 1 is a plan view of a fixture provided with my improved head.

Fig. 2 is a view in end elevation looking 40 from the left of Fig. 1.

Fig. 3 is a sectional view on a vertical plane of the bubbler head and the end of the supply pipe on which it is mounted.

Fig. 4 is a detail bottom view of the bubbler head with the pipe removed.

Fig. 5 is a detail plan view of the supply pipe showing the attaching means.

Fig. 6 is a view showing the bubbler head and pipe coupled, being a section on substantially the line 6—6 of Fig. 3.

Figs. 7 and 8 are perspective views of the bubbler head in different positions, showing the drinking stream and the wash of the head and adjacent parts.

55 Referring to the drawings by numbers, like numbers indicating like parts in the

several views, 10 indicates the supply fitting which may be of any suitable type, for it will be understood that the present invention is applicable to supply fittings of any 60 design and other than that shown. The fitting 10 is provided with a valve and valve operating means, as handle 11, by which the flow of the drinking stream is controlled.

The supply pipe 10 is provided at its de- 65 livery end with a fitting 12 having a vertical delivery passage 13 therein, and having, as well, suitable means for securing the bubbler head in place, these means in the present instance comprising lugs 14 which 70 engage offset openings 15 in the bottom of the bubbler head, as shown in Fig. 4, so that the lugs 14 on the upstanding neck 16 of the fitting 12 will enter these apertures and by giving the parts a quarter turn the lugs 75 14 will engage a groove 17 in the bubbler head and secure the parts firmly together, any suitable cement or binder being used to give a tight joint.

The bubbler head 18 is preferably, though 80 not necessarily, formed of vitreous material, as, for example, porcelain, and is preferably spherical in form so as to give a smooth, unbroken surface without crevices therein, although it may be varied as to form to a con- 85 siderable degree, the main desideratum being that the head present a smooth, unbroken surface devoid of sharp angles and crevices. Projecting outwardly and upwardly from one side of the head 18 is the 90 guard 19, substantially in the form of a half cup, this shell 19 being placed on that side of the bubbler head 18 from which the fountain is used, so as to provide a guard which will prevent the user bringing the mouth in 95 contact with the head 18, and, furthermore, receive the waste and divert it away from the person drinking. The guard 19 joins the head 18 by smooth curved joints, there being no interstices for the lodgment and 100 retention of contaminating matter, and the top or rim 20 of the guard 19 is smoothly rounded, and its juncture with the guard 19 is by means of smooth, unbroken curves, so that all sharp angles tending to form crevices are eliminated. The guard 19 is pref- 105 erably connected to the surface of the head 18 at a point above a horizontal plane passing through the center of the head.

It will be observed that the top or rim 20 110 of the guard 19 is bulged or enlarged somewhat so that it is thicker than the wall of

the guard 19, as shown in Figs. 3, 7 and 8, and that its ends 21 project over and beyond the edge of the guard wall 19, this edge 22 curving downwardly and slightly rearwardly to the body 18, all of these sections joining each other on smooth, unbroken curves so as to eliminate any sharp angles or crevices.

This construction in use produces the action of the water which is graphically illustrated in Figs. 7 and 8. The stream rises to the desired or regulated height from the jet orifice to a point above the rim convenient to the drinker, who may drink without, 10 however, being able to bring the lips to the jet orifice. The waste water falling will flow over the head 18 which, being formed on a smooth, unbroken curve, will direct the water downwardly without any splashing 15 or spattering thereof, and it is obvious that no contaminating matter can possibly lodge upon the surface of the head 18 but will be quickly carried away by the waste water.

The waste falls with considerable force 25 upon the spherical bubbler head 18, and on the open side of the bubbler head will, of course, follow the curve of the head 18 downwardly to be discharged, as shown in Fig. 8. On the opposite side of the bubbler 30 head, that from which the guard 19 projects, this waste water will flow with equal force downwardly over the spherical surface of the bubbler head 18, but, striking the curved surface 18' joining the head 18 and 35 the guard 19, will be diverted and turned without any break in the current against and upwardly along the curved inner face of the guard 19, as shown in Fig. 8, and as the flow from the falling bubble is constant 40 this stream or sheet of water will be urged constantly up the inner wall of the guard 19 to the point where gravity and friction overcome it, and then seeking an outlet will sweep around the sloping ends 22 of the 45 guard, and following the outer surface of the guard 19, and adhering thereto by reason of the surface tension, will meet at the point 23, Fig. 7, the united stream then flowing downwardly over the fixture, falling 50 to any suitable waste trap or receptacle below the fountain. Owing to the curved construction and smooth joints of all of the parts no splashing will take place, but the flow will be smooth and unbroken with the 55 final waste directed downwardly over the wall of the head 18, its curved wall leading the water, of course, around it as it flows downwardly so as to consolidate it and bring the waste stream to a point directly 60 beneath the head 18 from which it will be delivered.

The action of the stream in practice is illustrated in Figs. 7 and 8. It rises as a bubble to the desired or regulated height 65 above the rim 20, so as to be convenient to

the drinker. The waste water falling will strike the spherical surface of the head 18, as heretofore described, thoroughly cleansing it. That portion of the waste which falls onto the spherical surface of the head 70 adjacent the half cup or guard 19 will flow upwardly in a complete cleansing sheet, as hereinbefore described, namely, to the rim 20, and will then flow outwardly around the ends 22 of the guard 19, and continuing 75 around the outer surface thereof until it joins centrally, flows downwardly to any suitable waste trap or receptacle.

It is obvious that by this construction the user will be protected against any outward 80 splashing of the stream by the guard 19, but at the same time the waste is so turned and directed as that an effective washing of the head and guard is secured. It will be seen that the construction is such that no 85 crevices or angles exist for lodgment of any matter on the head, and, furthermore, that there is a moving sheet of water at all times over and about the parts, and that no opportunity exists for the collection or 90 standing of any water which falls from the bubble; the construction being such that a constant and natural drainage of water occurs.

In order to further consolidate and direct 95 the drip from the head so far as possible into a solid stream, I preferably form the fitting 12 as shown with a depending tip 24 which may be of any suitable shape, a cone shaped tip being shown in Figs. 2, 100 3 and 7, and a pyramidal form being shown in Fig. 8, so that the waste following the surface of the tip will be delivered therefrom in a substantially solid stream and disagreeable splashing or scattering of the 105 waste is avoided.

I claim:

1. A bubbler head for sanitary drinking fountains, comprising a body portion having a drinking stream outlet, and an imperforate splash-preventing guard formed integrally with said body portion and extending outwardly and upwardly from one side only thereof to a point above the top of the 110 said body portion.

2. A bubbler head for sanitary drinking fountains, comprising a substantially spherically shaped body portion having a drinking stream outlet and an imperforate splash-preventing guard integrally formed with said 115 body portion connected thereto at a point below the top thereof, said guard extending outwardly and upwardly from one side only of said body portion.

3. A bubbler head for sanitary drinking 125 fountains, comprising a body portion having a drinking stream outlet, and an imperforate splash-preventing guard extending outwardly and upwardly from one side of said body portion, the top of said guard 130

projecting at its ends beyond the side edges of the body portion of said guard.

4. A bubbler head for sanitary drinking fountains, comprising a body portion having a drinking stream outlet, the walls of said body portion sloping outwardly and downwardly from said outlet, and a substantially half cup-shaped imperforate splash-preventing guard extending outwardly and upwardly from one side of said body portion, the side edges of said guard curving inwardly toward each other and downwardly to said body portion to provide overhanging projections at the top of said guard.

15 5. A bubbler head for sanitary drinking fountains, comprising a body portion having a drinking stream outlet, and an imperforate splash-preventing guard of substantially half cup-shape formed integral with 20 said body portion and projecting outwardly and upwardly from one side of said body portion.

25 6. A bubbler head for sanitary drinking fountains, comprising a body portion, substantially spherical in shape, and provided with a drinking stream outlet at its top, and an imperforate splash-preventing guard of substantially half cup shape formed integral with said body portion and extending 30 outwardly and upwardly from said spherical body portion to a point above the top of said body portion.

35 7. A bubbler head for sanitary drinking fountains comprising a body portion having a substantially spherical top and a drinking stream outlet therein, and an imperforate splash-preventing guard of substantially half cup-shape formed integral with said body portion and projecting outwardly and upwardly from the upper spherical surface of said body portion.

40 8. A bubbler head for sanitary drinking fountains having a body portion of substan-

tially spherical shape provided with a drinking stream outlet therein, and an imperforate splash-preventing guard of substantially half cup shape integral with said body portion, and joined thereto on curved lines so as to eliminate abrupt angles and crevices.

45 9. A bubbler head for sanitary drinking fountains, comprising a body portion having a substantially spherical top and a drinking stream outlet therein, an imperforate splash - preventing guard of substantially half-cup shape extending outwardly and upwardly from one side of said body portion to a point above the top of said body portion, said guard having a thickened inwardly projecting top or rim substantially 50 circular in cross section, and the side edges of said guard sloping inwardly toward each other and downwardly to the body portion to form overhanging projections at the top of the guard.

55 10. A bubbler head for sanitary drinking fountains, comprising a spherical body portion of vitreous material having a drinking stream passage therethrough, an imperforate guard formed integral with said body portion and extending outwardly and upwardly from one side thereof, and a connecting member secured to the bottom of said body portion, said member having therethrough a drinking stream passage and provided 60 with a cone shaped projection at its bottom to collect and solidify the waste water coming from the bubbler head.

70 In testimony whereof I have hereunto set my hand in presence of two subscribing witnesses.

PHILIP MUELLER.
